UNITED STATES PATENT OFFICE.

HAROLD ABRAM EVANS, OF LYNN, MASSACHUSETTS, ASSIGNOR, BY DIRECT AND MESNE ASSIGNMENTS, TO PARCO SPECIALTY CO., OF LYNN, MASSACHUSETTS, A CORPORATION OF MASSACHUSETTS.

BOOT AND SHOE MANUFACTURE.

Application filed August 12, 1925. Serial No. 49,768.

The present invention, though having fields of more general usefulness, is more particularly related to the art of boot and shoe manufacture. From a more limited aspect, it relates to shoe uppers having French-cord binding strips folded around their edges, and to methods of making such uppers.

According to present-day practice, the binding strip, after it is sewed to the upper, and an adjacent portion of the upper, are coated with wet cement, after which the strip is folded around the edge of the sheet to which it is sewed, and the folded strip is pressed into contact with the sheet. The use of the wet-cement pots in the shoe factory is objectionable.

An object of the invention, therefore, is to improve upon present-day practice, to the end of producing a better French-corded upper. Other objects will appear herein-after and will be pointed out in the appended claims.

The invention will now be explained in connection with the accompanying drawings, in which Fig. 1 is a section of a shoe upper manufactured according to the present invention, showing a binding strip sewed thereto, prior to the folding operation; Fig. 2 is a similar section showing the binding strip already folded, and Figs. 3 to 7 are views illustrating a preferred method of manufacturing the improved binding strip of the present invention.

According to the present-day practice, a French-cord binding strip 2 is first sewed at 12, along the edge 8 of the two longitudinally disposed edges 8 and 26, to a face 10 of a shoe upper 6, along an edge 4 of the upper. The upper 6 may be constituted of leather, cloth, or any other desired material and the binding strip may be constituted of cloth, silk, leather, and the like. The binding strip is usually a grosgrain, galloon or similar fabric having its edges 8 and 26 selvedged. It is sufficient to have the edge 8 alone selvedged, the weaving of this selvedged edge preventing the strip from tearing away along the stitches 12. Resulting from the manner in which the sheet and the strip are sewed together, they are generally in more or less close parallelism, as shown in Fig. 1. Wet cement is then applied to the other face 16 of the shoe upper, along the margin near

the edge 4, and to the whole face 14 of the strip 2, after which the binding strip is folded around the secured-together edges 4 and 8 and pressed flat into contact with the face 16 of the shoe upper. The binding strip is held in contact with the face 16 by the cement, but the use of the wet cement is a troublesome factor in shoe factories.

According to the present invention, the binding strip is cemented prior to its introduction into the shoe factory. It is preferred to use a wet cement, gum, or the like. The presence of the cement upon the binding strip prior to its sewing to the shoe upper would cause inconvenience during the sewing operation causing, among other things, the stock to drag during the sewing. The cement is therefore covered with a covering strip 19. The covering strip serves the further function of keeping the cement air tight and preventing its deterioration. This covering strip may preferably be of some suitable woven material. After the binding strip 2 has been sewed to the upper, the covering strip 19 is pulled away to expose the cement upon the binding strip. The binding strip is then folded in the customary way, as indicated in Fig. 2. The folding may be done by hand or by machine.

To prevent sewing the covering strip 19 to the shoe upper along with the binding strip 2, the covering strip 19 is caused to cover a portion only of the face 14 of the binding strip. This portion extends from the free edge 26 of the binding strip to any desired point 18, Figs. 1 and 2. It is thus possible for the sewing needle to pierce the portion of the binding strip between the edge 8 and the point 18, which portion is left uncemented. Depending upon the position of the point 18, therefore, the cement may be coated over a larger or smaller area of the binding strip, as desired. The point 18 should preferably be chosen such that it will be disposed adjacent to the corner of the shoe upper. The cement will not, then, tend to engage and stick to the edge 4 of the shoe upper, and thus resist the effort of the operator to pull the strip tightly around the edges 4 and 8, which would result in a baggy fold. Best results are obtained when the edge 4 of the upper engages uncoated portions only of the strip.

The cement and the covering strip 19 may

be applied to the binding strip 2 in many different ways, all within the scope of the invention. A preferred method is to feed the binding strip 2, as it is unrolled from a reel 30, between tension rolls or pins 32, and through a cement pot 34, along the bottom thereof. This bottom is provided with a longitudinally disposed opening 36 about as wide as the width of the binding strip 2, a portion of which opening is covered with a longitudinally disposed metal plate 38. The cement in the pot 34 rests on the metal plate 38 and is prevented from falling through the opening 36 by a metal plate 40 that is sprung upward towards the bottom of the cement pot to close the opening 36. A valve (not shown) may close the opening 36 when the apparatus is not in use. The binding strip is fed from the reel 30 between the plates 38 and 40, so that so much only thereof becomes cemented as is exposed in the opening 36. The gum or cement is forcibly caused to adhere to the binding strip by weights (not shown). The partially cemented strip is then passed beyond a knife 41 that scrapes the cement clean and through an oven 42, where the cement becomes partly dried into paste form. After passing through the oven, the binding strip 2 is led to rolls 44. Before it reaches the rolls 44, the cemented portion thereof becomes covered with the covering strip 19, led from a reel 46 through a suitable guide 48. The rolls 44 press the strips 2 and 19 firmly together and feed the completed binding strip into a receptacle 50. The completed binding strip is wound into reels and supplied in reel form to the shoe factories.

It will be understood that the invention is equally applicable to other articles than that which is herein chosen for the purposes of illustration, and the elements of the article need not necessarily be of the relative dimensions shown. It may be desirable, for example, to fold an element of relatively large dimension over the edge of an element of relatively small dimension. For definiteness, all such elements that are to be folded will be referred to in the claims as the "strip" and the element about the edge of which the strip is to be folded will be referred to as the "sheet", though the adopted terminology may not be strictly applicable to the specific article which may be under consideration.

The invention is not restricted to the exact embodiment that is illustrated and described herein, but modifications may be made by persons skilled in the art without departing from its spirit and scope, as defined in the appended claims.

What is claimed is:

1. The method of making an article of the class described, which comprises coating one longitudinally disposed marginal portion of

an elongated strip with adhesive material while leaving the remainder of the strip uncoated, covering the coated portion of the strip with a temporary covering tape, sewing the uncoated edge of the strip to the marginal portion of a sheet, and subsequently removing the covering tape from the coated portion of the strip, whereby sewing of the strip to the sheet is not hindered by adhesive material and whereby the margin of the strip may be adhesively secured to the sheet.

2. The method of finishing the edge of sheet material, which comprises coating one marginal face of a binding strip with moist adhesive material while leaving the remainder of the strip uncoated, applying a temporary covering tape to the coated portion of the binding strip, leaving the opposite edge of the binding strip uncovered, securing the uncovered edge of the strip to a marginal face of the sheet, removing the covering tape, folding the binding strip over the edge of the sheet, and pressing its coated margin into adhesive engagement with the opposite marginal face of the sheet.

3. The method of finishing the edge of sheet material, which comprises coating one marginal face of a binding strip with moist adhesive material while leaving the remainder of the strip uncoated, permitting the moist adhesive partially to dry, thereupon applying a temporary covering tape to the coated portion of the binding strip, securing the uncovered edge of the strip to a marginal face of the sheet, removing the covering tape, folding the binding strip over the edge of the strip, and pressing its coated margin into adhesive engagement with the opposite marginal face of the sheet, without necessity of the application of heat or moisture to the coated portion of the tape.

4. As an article of manufacture, an elongate binding strip, one of the two longitudinal edges of which is selvedged, the strip having an adhesively coated face adjacent the other longitudinal edge and a temporary covering tape adhesively applied to a partial width of the strip including the coated portion, whereby the selvedged edge of the strip is adapted to be sewed to the edge of a sheet without hindrance from the temporarily covered adhesive.

5. An adhesive tape having a portion of one side extending along one edge of the tape coated with adhesive and having another portion on the same side which is uncoated with adhesive, and a protective strip of less width than the tape for covering said coated portion.

In testimony whereof, I have hereunto subscribed my name.

HAROLD ABRAM EVANS.
